UNITED STATES PATENT OFFICE

ROBERT R. GONSETT, OF LOS ANGELES, CALIFORNIA, ASSIGNOR OF ONE-SIXTEENTH TO VIRGIL V. ULLOM, ONE-SIXTEENTH TO WESLEY D. SPENCER, ONE-SIXTEENTH TO HOWARD A. BURRELL, AND ONE-SIXTEENTH TO BUCK WALKER, ALL OF LOS ANGELES, CALIFORNIA

ADJUSTABLE ACCESSORY TIME SWITCH

Application filed February 1, 1928. Serial No. 251,111.

My invention relates to a new and novel type of time switch which is particularly useful as an accessory, being so constructed as to be readily interposed between a power circuit and an auxiliary circuit to which the electric current is to be supplied.

It is an object of my invention to produce a device which is simple and economical in construction, comprising parts which may be easily inserted in an ordinary alarm clock, affording a switch control which is accurate in adjustment, neat in appearance, and which may be readily adapted to either a domestic or commercial use; my invention being particularly valuable for such domestic purposes as the control of electric washing machines, coffee percolators, etc., as well as in the control of electric signs.

A further object of my invention is to provide a type of time switch in which I may use a novel form of electrical connection similar to that shown in my copending application, Serial No. 136,884, filed September 21, 1926, by means of which the same may be conveniently attached in any electrical connection as commonly used both for domestic and advertising purposes.

Other objects and advantages of my invention, including a mechanism which may be incorporated in an ordinary alarm clock, by means of which it may be set to ring at two separate and distinct periods, will be better understood from the following description of the accompanying drawings, illustrating an embodiment of my invention, and in which

Fig. 1 is a diagrammatic view illustrating one embodiment and use of my invention,

Fig. 2 is a plan view with parts removed, showing clock assembly embodying features of my invention,

Fig. 3 is an elevational view in the direction of arrow 3 in Fig. 2,

Fig. 4 is a partial sectional view along the line 4-4 of Fig. 2,

Fig. 5 is a partial sectional view along the line 5-5 of Fig. 2,

Fig. 6 is a partial section along the line 6-6 of Fig. 2,

Figs. 7 and 7a are elevational views show-

ing a switch assembly used in connection with an embodiment of my invention,

Figs. 8, 8a and 8b are elevational views showing the relation of parts in the control mechanism of my invention in a "set", a "switch closing", and a "switch opening" position, respectively.

Fig. 9 is a partial sectional view illustrating a type of electrical connection employed in my invention.

More particularly describing my invention as herein illustrated, 11 indicates a clock-switch, connected by means of an electrical conducting member 12, with a socket-plug connection 13; the connection 13 being shown as mounted between a wall socket 14 (connected with an electrical circuit 15-16) and a plug 17, the plug, in turn, being shown as connected through an auxiliary conductor 18 with an electrically controlled device, such as the sign 19, but may be any electrical commercial or domestic device, such as an electric heater, percolator, etc.

The clock 11, which is illustrated with parts removed in Fig. 2, may be of the ordinary "alarm clock" type, having an alarm winding key 20, mounted upon an alarm operating shaft 21, the shaft being provided with a driving spring 22, and with a control gear 23. The gear 23 is in mesh with a pinion 24 which is integral with a ratchet shaft 25, having a ratchet 26 mounted thereon. The ratchet 26 is engageable by a dual pawl 27, which is rigidly mounted on an oscillating control shaft 28; the shaft 28, in turn, carries an outwardly extending arm 29, the purpose of which will be hereinafter explained. It will be obvious from Fig. 2, to all persons familiar with this type of clock construction, which is common, and to which I make no claim, that the rotation of the shaft 21, which I may term the switch or alarm operating shaft, is governed by the pawl and ratchet 27 and 26 respectively, and that as long as the arm 29 is permitted to oscillate freely, the shaft 21 will be rotated by the spring 22, unless otherwise prevented by external means.

The electrical switch, which I employ in my invention and which is operated by the

shaft 21, is generally indicated at 30, and 61, and forwardly mounted upon the gear comprises an insulating member 31 having a 58 I provide a secondary or front cam collar 62 provided with a cam notch 63, the collars being rigidly interconnected one with the other and the notches 61 and 63 being in alignment, and bearing a definite fixed relation with the time indicating hand and dial 56 and 57. The numeral 64 indicates a rearward or primary engagement member comprising a sleeve 65 provided with an outwardly extending projection 66 which is adapted to rest upon the rear cam collar 60 and to be received by the notch 61. The engagement member or sleeve 65 is further provided with an annularly grooved flange 68 adapted to receive a spring friction brake member 69, the brake member 69 being held in a fixed position through engagement with a hook 70 formed upon a laterally fixed arm 71. The arm 71 is slidably mounted upon the control shaft sleeve 55 and is held against rotation through engagement with the pawl supporting shaft 28 in a notch 72 formed in the arm 71, shown in Fig. 5. It will be understood that the mentioned primary engagement sleeve 65 is rotatable about the control sleeve 55 but is held against rotation therewith by means of the friction brake 69. In order that the rearward or primary engagement member 65 may be set in any desired angular position relative to the control shaft and sleeve, I provide the setting shaft 51 with a primary setting collar 75 which is held in rigid relation to the shaft 51 by means of a key 76, and is provided with a 100 forwardly extending finger 77 adapted to engage the projection 66 on the engagement member 64. The engagement member 64 and attending parts are held in a positive engaging relation to the cam collar 60 by means of a resilient spring finger 78, which is mounted upon one of the clock frame supporting shafts 79, receives the control sleeve 55 in a longitudinal aperture 80 (as indicated in dotted lines in Fig. 5) and extends therebeyond 110 in a projecting finger 81 which has a forwardly extending hook 82 formed thereon, the hook being adapted to engage a corresponding hook 83 formed on the extending end of the oscillating arm 29, when the projection 66 115 rides upon the forward face 84 of the primary cam collar 60, as is best illustrated in Fig. 8. It will be understood from Figs. 8 and 8a that when the projection 66 drops into the cam notch 61, the projecting finger 81 correspondingly drops, permitting the oscillation of the arm 29 until such oscillation and the resultant rotation of shaft 21 is otherwise checked, as will hereinafter be explained.

Rotatably mounted upon the shaft 51, I provide what I may term a control sleeve 55, upon the forward end of which is mounted a gear 58. The gear 58 is connected through a train of gears 59 with the clock mechanism (not shown), the ratio of the gears being such that the sleeve 55 is carried through one revolution during a twelve hour period of the clock. Rearwardly and integrally mounted upon the sleeve 55, I provide what I may term a "primary" cam collar comprising a rear cam 60 provided with a cam notch

Numeral 90 indicates what I term a "secondary" engagement member which is rigidly mounted upon the forward end of the setting shaft 51, and is provided with a projection 91 adapted to rest upon the forward face 92 of 130

the secondary cam collar 62, and is adapted to receive the notch 63 of the cam 62. Immediately below the gear 58 and slidably engaging a shoulder 93 formed thereon, I provide a secondary resilient finger 94, which 5 rotatably receives the control sleeve 55 in an aperture 95 and has a constant forward thrust thereon transmitted through the shoulder 93. The finger 94 is shown as being mounted upon the frame supporting shaft 10 79 above a frame plate 96, and the extending end 97 thereof is provided with a rearwardly extending hook 98 which is adapted to engage the hook 83 formed on the oscillating 15 arm 29, as shown in Fig. 8a. It will be understood that when the cam notch 63 is rotated to a position opposite the projection 91 that the forward thrust of the resilient finger 94 carries the sleeve and attending parts to the position shown in Fig. 8b, and is incidentally disengaged from the hook 83, permitting the movement of the oscillating arm 29 and the attending secondary rotation of 20 the switch operating shaft 21 until such rotation is otherwise checked by the binding action between the rod 39 and the shaft 21, as 25 shown in the dotted line position in Fig. 7.

In order that the switch operating shaft 21 may be permitted to have a limited 30 "switching" rotation between the disengagement of the primary finger 81 and the engagement of the secondary finger 97 with the oscillating arm 29 (as illustrated in Figs. 8 and 8a), I provide what I may term a secondary finger supporting plate 100, the form of 35 which is substantially a circular segment, as is best shown in Figs. 3 and 4. This plate 100 is fixed to the switch operating shaft 21, and is so formed that the forward edge 101 40 (relative to the "switching" rotation of the shaft 21) of the front face 102 of the plate 100 is in engagement with the rearwardly projecting hook 98 of the secondary finger 97 when the switch is in a set position, as 45 is best illustrated in Figs. 3 and 8. It will therefore be understood that when the primary finger 81 drops to the position shown in Fig. 8a that the plate 100 must be rotated by the shaft 21, to the dotted line position C 50 shown in Fig. 3, before the hook 97 on finger 94 may be permitted to drop to the position shown in Fig. 8a.

It will further be understood that the angular segment of the plate 100 is made of 55 such dimensions to permit the rotation of the operating shaft 21 to the position shown in Fig. 7a, at which point the circuit is closed. The limitation of the secondary movement of the shaft 21 is controlled by the arm 39 and 60 the groove 38, as shown in the dotted line or off position illustrated in Fig. 7.

The type of socket-plug connection which I propose to use in my invention, in order that the switch may be conveniently used as a 65 domestic accessory, a form of which is shown

in my copending application Serial No. 136,834, filed September 21, 1926, is illustrated in section in Fig. 9, and comprises a socket 110 adapted to receive a plug 111, and provided with connecting prongs 112-112' 70 which are adapted to be received in any of the standard forms of wall sockets, etc., as indicated in dotted lines at 113. The socket 110 comprises a shell conductor 114 and a central stem conductor 115, the shell conductor being directly connected with prong 112', and the central conductor 115 being connected with prong 112 through a separate circuit comprising wires 35 and 35' which comprise the conducting member 12 and extend to and 75 are connected with the conducting plates 34, 34' (Fig. 2) of the time switch 30, through which the circuit is completed.

It will be understood that, in the operation of my invention, the indicating hand is first 80 turned in a counterclockwise direction by the adjusting member 54, to the hour at which it is desired for the switch to be turned on, (or the alarm to initially ring) such as position "a", Fig. 1, and is then rotated in a clockwise 85 direction to the hour at which the switch is to be turned off, (or at which the alarm is to finally ring) such as position "b", Fig. 1, the respective primary and secondary engagement members 64 and 90 assuming positions 90 somewhat as illustrated in Fig. 8. The switch 30 is then "set" as shown in the full line position in Fig. 7. As was described above in connection with the switch governing mechanism 50, the primary movement of 100 the switch is effected when the control sleeve 55 is rotated to the position relative to the primary engagement member 64, where the projection 66 is opposite the cam notch 61, as shown in Fig. 8a, and the rotation of the 105 switch operating shaft 21 is permitted, turning the switch to the contacting position shown in Fig. 7a. The secondary or turning off movement of the switch is effected when the control sleeve 55 has been revolved to the 110 position shown in Fig. 8b when the secondary cam notch 63 is opposite the projection 91 on the forward or secondary engagement member 90, the rotation of shaft 21 being permitted by freeing the oscillating arm 29 and continuing until the dotted line position of the switch arm 36 shown in Fig. 7 has been 115 assumed.

It is a fundamental feature of novelty of 120 my invention that same may be used in an ordinary alarm clock, with comparatively little rearrangement of parts, providing an accessory which is accurate and simple in its adjustment and which may, when not in use 125 as a time switch, be used as an ordinary clock, since the switch operates independently of the clock mechanism, it being further understood that, if desired, the governing means may be used independently of the switch for operat- 130

ing an alarm clock at any two separate periods of time.

I claim as my invention:

5. In combination with a timing device of the alarm clock type: a normally open switch member; switch operating means including a shaft having a drive spring mounted thereon; switch governing means; and clock means for operating said switch governing means, said governing means comprising a setting shaft provided with time indicating means, means for manually rotating said shaft in opposite directions, a forward and a rearward cam member rotatably mounted on said shaft and rigidly connected one with the other, a rearward engagement member rotatably mounted on said shaft and laterally movable relative to said cam members, means yieldably holding said rearward engagement member in engagement with said rear cam member, and means operable by the downward movement of said engagement member permitting a limited primary rotation of said switch operating shaft.
23. 2. In combination with a timing device of the alarm clock type: a normally open switch member; switch operating means including a shaft having a drive spring mounted thereon; switch governing means; and clock means for operating said switch governing means, said governing means comprising a setting shaft provided with time indicating means, means for manually rotating said shaft in opposite directions, a forward and a rearward cam member rotatable with respect to each other and rotatably mounted on said shaft and rigidly connected one with the other, a rearward engagement member rotatably mounted on said shaft and laterally movable relative to said cam members, means yieldably holding said rearward engagement member in engagement with said rearward cam member, and means operable by the rearward movement of said engagement member permitting a limited primary rotation of said switch operating shaft, said setting shaft being provided with means for the angular adjustment of said rearward engagement member.
31. 3. In combination with a timing device of the alarm clock type: a normally open switch member; switch operating means including a shaft having a drive spring mounted thereon; switch governing means; and clock means for operating said switch governing means, said governing means comprising a setting shaft provided with time indicating means, means for manually rotating said shaft in opposite directions, a forward and a rearward cam member rotatably mounted on said shaft and rigidly connected one with the other, a rearward engagement member rotatably mounted on said shaft and laterally movable relative to said cam members, means yieldably holding said rearward engagement
- member in engagement with said rearward cam member, and means operable by the rearward movement of said engagement member for permitting a limited primary rotation of said switch operating shaft, said setting shaft being provided with a forward engagement member, resilient means holding said forward cam in engagement therewith and means operable by the forward movement of said forward cam relative to said forward engagement member permitting a limited secondary rotation of said switch operating shaft.
4. In combination with a timing device of the alarm clock type: a normally open switch member; switch operating means including a shaft; means for rotating said shaft; and pawl and ratchet means permitting the rotation of said shaft, means governing the operation of said pawl and ratchet including a setting shaft having a plurality of cams rotatably mounted thereon, clock means for rotating said cams and cam engaging members mounted on said shaft, said cam engaging member being angularly adjustable with respect to each other.
5. In combination with a timing device of the alarm clock type: a normally open switch member; switch operating means including a shaft; means for rotating said shaft; and pawl and ratchet means permitting the rotation of said shaft, means governing the operation of said pawl and ratchet including a setting shaft having a plurality of cams rotatably mounted thereon, clock means for rotating said cams and cam engaging members mounted on said shaft, said cam engaging members being angularly adjustable with respect to each other and means for yieldably holding said cams in engagement with said engagement members.
6. In combination with a timing device of the alarm clock type: a normally open switch member; switch operating means including a shaft; means for rotating said shaft; and means operable to prevent the rotation of said shaft including an oscillating arm; and control means governing the movement of said oscillating arm comprising a pair of resiliently movable fingers adapted to independently engage said arm, a setting shaft, and cam means mounted on said setting shaft for holding one of said fingers in engagement with said arm and adapted to permit the transverse movement of both of said movable fingers at predetermined intervals of time.
7. In combination with a timing device of the alarm clock type: a normally open switch member; switch operating means including a shaft; means for rotating said shaft; and means operable to prevent the rotation of said shaft including an oscillating arm; and control means governing the movement of said oscillating arm comprising a pair of

resiliently movable fingers adapted to independently engage said arm, a setting shaft, cam means mounted on said setting shaft for holding one of said fingers in engagement with said arm and adapted to permit the transverse movement of both of said movable fingers at predetermined intervals of time, and a segmental plate member rotatable by said switch operating shaft for holding one of said fingers in engagement with said oscillating arm during a predetermined period of operation.

8. In combination with a timing device of the alarm clock type: an alarm operating shaft; means for operating said shaft; governing means for controlling the operation of said shaft; clock means operating said governing means; said governing means including an indicator rotatable in opposite directions; means operable by the rotation of said indicator in one direction whereby said governing means are set to control the operation of said alarm shaft at a predetermined period; and means operable by the rotation of said indicator in an opposite direction whereby said governing means are set to control the operation of said alarm shaft at a second predetermined period.

9. In combination with a timing device of the alarm clock type: an alarm operating shaft; governing means for controlling the operation of said shaft; clock means for operating said governing means; said governing means comprising a setting shaft provided with time indicating means; means for manually rotating said shaft in opposite directions; a forward cam member and a rearward cam member rotatably mounted on said shaft and rigidly connected one with the other; a rearward engagement member coaxially mounted on said shaft and laterally movable relative to said cam members; means yieldably holding said rearward engagement member in engagement with said rearward cam member; and means operable by the rearward movement of said engagement member permitting a limited primary rotation of the alarm operating shaft; said setting shaft being provided with a forward engagement member, which is angularly adjustable with respect to said rearward engagement member, resilient means holding said forward cam member in engagement therewith; and means operable by the forward movement of said forward cam member relative to said forward engagement member permitting a secondary rotation of said alarm operating shaft.

10. In combination with a timing device of the alarm clock type: an alarm operating shaft; a setting shaft; an indicator operable by said setting shaft; a time period indicating dial cooperating with said indicator; and alarm governing means controlled by the rotation of said setting shaft in oppo-

site directions, said governing means being effective to permit a primary limited rotation of said alarm operating shaft at a predetermined period indicated by an initial position of said indicator relative to said dial, and to permit a secondary rotation of said alarm operating shaft at a second predetermined period indicated by a final position of said indicator relative to said dial.

In testimony whereof, I have hereunto set my hand at Los Angeles, California, this 18th day of January, 1928.

ROBERT R. GONSETT.
